(57) **CLAIM**

The ornamental design for a cyclometer, as shown and described.

DESCRIPTION

FIG. 1 is a perspective view of a cyclometer showing my new design;

FIG. 2 is left side elevational view showing the design for the cyclometer of FIG. 1;

FIG. 3 is a right side elevational view showing the design for the cyclometer of FIG. 1;

FIG. 4 is a front elevational view showing the design for the cyclometer of FIG. 1;

FIG. 5 is a rear elevational view showing the design for the cyclometer of FIG. 1;

FIG. 6 is a top plan view showing the design for the cyclometer of FIG. 1; and,

FIG. 7 is a bottom plan view showing the design for the cyclometer of FIG. 1.

The broken lines shown in the drawings illustrate portions of the cyclometer that form no part of the claimed design.
